UNITED STATES PATENT OFFICE.

CHARLES A. DU POY, OF OMAK, WASHINGTON.

COOLING SYSTEM FOR ENGINES.

Application filed November 15, 1922. Serial No. 601,120.

To all whom it may concern:

Be it known that I, CHARLES A. DU Poy, a citizen of the United States, residing at Omak, in the county of Okanagon and State 5 of Washington, have invented certain new and useful Improvements in Cooling Systems for Engines, of which the following is a specification.

This invention relates to improvements in 10 the cooling systems of internal combustion engines.

The primary object of this invention is the provision of an improved device for aerating the liquid cooling medium as used 15 in connection with the cooling systems of internal combustion engines.

An important object of the invention is the provision of a relatively simple and practical arrangement for the combined utilization of air and liquid cooling mediums 20 for internal combustion engines.

A further object of the invention is the provision of an improved cooling arrangement for engines which utilizes air and 25 cooling mediums, and an improved arrangement for effecting the mixing and circulation of the mediums.

A further object of the invention is the provision of an improved arrangement of 30 the above described character, embodying practical advantages over those types of cooling systems utilizing liquid and air mixed cooling mediums, in that the fluid mixing and circulating means embodied in the improved system operates through a combination of air and liquid instead of a solid liquid mass, permitting the driving of the mixing and circulating means with relatively little power, and effectively and minutely aerating the liquid mass.

Other objects and advantages of this invention will be apparent during the course of the following detailed description.

In the accompanying drawings, forming 45 a part of this specification, and wherein similar reference characters designate corresponding parts throughout the several views,

Figure 1 is a fragmentary side elevation 50 of an internal combustion engine, showing certain conventional details of a cooling system, and embodying an improved arrangement for aerating a cooling medium such as water.

Figure 2 is a fragmentary and longitudinal cross sectional view, taken through

the improved liquid aerating mechanism as embodied in an internal combustion engine cooling system.

Figure 3 is an enlarged transverse cross 60 sectional view, taken substantially on the line 3—3 of Figure 2.

Figure 4 is an enlarged transverse cross 65 sectional view, taken substantially on the line 4—4 of Figure 2.

Figure 5 is a cross sectional view taken substantially on the line 5—5 of Figure 3.

Figure 6 is a cross sectional view taken substantially on the line 6—6 of Figure 3.

Figure 7 is a transverse cross sectional 70 view, taken substantially on the line 7—7 of Figure 2.

In the drawings, wherein for the purpose of illustration is shown but the preferred embodiment of this invention, the letter A 75 designates an internal combustion engine of any approved type, which embodies a novel arrangement B, as used in the conventional cooling system C thereof for the effective aeration and circulation of a cooling liquid. 80

The internal combustion engine A may be of any approved type, preferably of the water cooled block type.

The cooling arrangement C ordinarily is 85 provided for internal combustion engines of the water cooled type, and may include the radiator 10, having internal combustion engine water manifolds 11 communicating upwardly therewith, and the outflow conduit 12 arranged at the bottom of said radiator for flow of water through the improved mechanism B, whereby water and cold air may intermingle and pass into the water pockets of the internal combustion engine A, as cooling mediums therefor. The fan 13 may be 90 included as a part of the cooling system C.

which is rotatably carried forwardly of the internal combustion engine A, and preferably being driven by means of the ordinary belt 14 directly from the crank shaft (not 100 shown). As is well understood, in the case of the thermo-syphon cooling system, the cooling medium passes through the water pockets in the internal combustion engine A, absorbing heat therefrom incident to operation, said water in its heated condition passing through the water manifold 11 into the upper portion of the radiator 10. The air, as is well understood, cools the water passing through the radiator 10, so that the cooler 105 portion of the water in the radiator passes downwardly therethrough, and into the con-

110

duit 12. The cooling liquid passes through the improved cooling apparatus B in a manner which will be subsequently described.

Referring to the construction of the mechanism B for aeration of a cooling liquid, the same includes a novel housing 20 providing a passageway for conducting of the cooling mediums into the internal combustion engine A, and having communication at its ends with the conduit 12 and the water intake opening of the internal combustion engine casing. This housing 20 preferably includes the front portion 21 which may be of cylindrical formation, and providing a water compartment 22 having direct communication with the water conduit 12 of the cooling means C, as by means of the downwardly extending pipe portion 23, the passageway 24 of which communicates directly with the water chamber 22. This front portion 21 is provided with a front wall 25, having a central opening 26 which is disposed in axial alignment with respect to the cylinder shaped housing portion 21. The rear of the portion 21 is provided with an inwardly extending flange 28, through which the compartment 22 opens, and is exteriorly provided with the screw threaded extension 27.

The housing 20 of the improved apparatus B also embodies the front casing portion 30, which is elongated in formation, and having a front cylindrical shaped end 31 which provides a compartment 33 therein of substantially the same transverse dimension as the compartment 22. This front end 31 is preferably provided with the annular flange 34 extending outwardly therefrom. The casing 30 or rear portion of the housing 20 is reduced rearwardly of the compartment 33, providing the annular shoulder or seat 36 which faces into the compartment 33 provided at the front end of the casing 30; said casing 30 rearwardly of the seat 36 providing a chamber 38, which is somewhat smaller in diameter than the chamber 33. From the chamber 38, the casing 30 is provided with a passageway 39, which leads rearwardly to the rear end of the casing 30, and opening upon said end. The rear end of said casing 30 is provided with the laterally extending flanges 40, being apertured as at 41 for reception of bolts, rivets or other attaching elements 42, whereby the rear end of the housing 20 may be attached to the cylinder block of an internal combustion engine, so that the passageway 39 may communicate with the water pocket of said internal combustion engine.

A coupling sleeve 43 is provided for cooperation with the sections 21 and 30 of the housing 20, which is interiorly screw threaded, as at 44, for engagement with the screw threads 27 of the section 21, and which includes an inwardly extending annular flange

45 for engagement with the outwardly extending annular flange 34 of the section 30, and whereby said sections 21 and 30 may be connected in leak proof manner by said coupling 43, as can readily be understood. 70

A member 50 is preferably employed as a part of the improved mechanism B, which includes a hollow bearing sleeve 51 adapted for axial extension through the compartment 22 of the housing section 21, and being 75 screw threaded as at 52 upon its front end, said screw threaded end 52 normally extending through the opening 26 in the front wall 25 of the casing 21 for adjustably receiving a clamping nut 54 outwardly of the compartment 22. An annular flange or spacing member 56 is preferably formed integral with the hollow tube 51, and adapted for engagement with the inner surface of the front wall 25, substantially as is illustrated 85 in Figure 2, whereby when the nut 54 is adjusted on the screw threaded end 52, the tube 50 will be effectively clamped to the front wall 25, and in leak proof connection therewith. The front end of the tube or bearing sleeve 50 is provided with a pair of spaced annularly extending flanges or discs, preferably cast integral therewith, and disposed in parallel planes. In position within the housing 20, these flanges 57 and 58 are 95 adapted for extension into the compartment 33 upon the forward end of the housing section 30, so that the same contact in leak proof connection the flange 28 and seat 36, to provide a chamber 59 intermediate said 100 flanges 57 and 58 which will be hereinafter referred to as the air chamber. When in this position, it can be readily understood that the disc portions 57 and 58 act as walls or barriers dividing the compartment 22 of 105 the section 21 from the smaller compartment 33 of the housing section 30. Both of the discs or walls 57 and 58 are provided with relatively large aligning openings 61, which are adapted for receiving tubes 62, the passageways 63 of which communicate the chambers 22 and 38. The front wall or disc 57 is otherwise impervious. However, the rear disc or wall 58 is preferably provided with a series of relatively small openings 64 provided transversely therethrough which communicate the air chamber 59 with the chamber 38. It can thus be seen that the chambers or compartments 22 and 38 are in communication through the tube passageways 110 63, while the air compartment 59 is in communication with the compartments 38 by way of the small openings 64 in the disc or wall 58. 115

The improved arrangement B preferably embodies a fluid mixing and impelling mechanism which may include the propeller 66, which is rotatably supported within the compartment 38 upon an end of a shaft 67, which rotatably extends through the 120 68, 130

bearing sleeve 51 and has the forward end thereof extending from said sleeve 50 and provided with a pulley member 68 keyed thereto, as at 69. The pulley 68 is provided with the annularly extending flanges 70, which provide a groove intermediate the same for reception of the fan belt 14 as a driving means for the propeller 66. A packing nut 71 is preferably provided upon the forward end of the screw threaded sleeve portion 52, in order to provide a leak proof connection about the propeller shaft 67. The blades 73 of the propeller 66 are of special formation, extending radially from the hub portion 74. The edges of said propeller blades 73, in direct facing relation with the rear wall 58 of the air compartment 59, are preferably hook shaped or overturned as at 76 in the direction of rotation of the propeller 66, and which are adapted to receive liquid and air from the chambers 22 and 59, treating the same in the most effective manner for complete aeration of a cooling liquid, and insuring circulation of the same as will be hereinafter noted.

Means 80 is preferably provided for effectively controlling the supply of air into the housing 20 as a cooling medium, and which includes a tubular shaped tank or casing 81, which is preferably vertically positioned, and having the same supported by means of horizontally extending tubes 82 attached to the forward end portion 31 of the housing section 30. These tubes 82 provide passageways 83 therethrough which establish communication between the air chamber 59 and the chamber 84 of the tank 81. A cap 86 is preferably screw threaded in the top of the air tube 80, which is preferably provided with the vertical passageway 87 therethrough. A valve member 88 is preferably movably carried by this cap 86 adapted for regulating atmospheric communication of the tube chamber 84.

In operation, the propeller 66 will be driven within the mixing chamber 38 upon operation of the internal combustion engine A, as can be readily understood by reason of the movement of the fan belt 14 over the pulley 68. The rotation of the propeller blades 73 will create a suction, which in addition to the thermo syphonic action of the cooling system will suck water or cooling liquid from the liquid chamber 22 through the passageways 63 of the tubes 62 into the mixing chamber 38. In similar manner, rotation of the propeller 66 will also draw air into the compartment 59, the valve 88, of course, being open. The air will pass through the relatively small openings 64 in the wall 58, and it can readily be understood that cool air and liquid will be fed together just behind the propeller 66, prior to mixing action with the blades 73. Thus the propeller does not have to

rotate through a solid body of liquid, but rotates through a mixture of air and liquid. The turned edges 76 of the propeller blades 73 insure a thorough swashing of the cooling mediums, so that the cooling liquid is thoroughly aerated. In addition to this, the propeller blades 73 are of such formation as to direct effective circulation of the thoroughly mixed cooling mediums through the mixing compartment 38 without creation of eddies.

It is obvious that during operation of the engine A, there will be a constant passage of water and air through the compartments 22 and 59 for mixture within the compartment or chamber 38. However, upon stopping of the engine A, the propeller 66 will likewise stop and it is probable that water will enter the compartment 59 through the openings 64. To offset any liability of escape of water or other cooling liquid from the valve passageway 87, a float valve 90 has been provided, which is of elongated formation and disposed within the air tube chamber 84 so that upon rising of the liquid level within this compartment 84, the upper convex arcuate end 91 of the float valve 90 may engage within the arcuate concavity 92 provided in the valve head 86 and effectively seal the air passageway 87 against liability of escape of cooling liquid. At times it may be desirable to drain all liquid contents from the various compartments of the internal combustion engine cooling system, and to effect a proper draining of the water or liquid from the air compartment 59, notches 95 have been provided in the lower edges of the walls 57 and 58 which permits draining of contents of the chambers 22, 38 and 59.

From the foregoing description of this invention it can be seen that a practical unit has been provided, by means of which water or other liquid may be effectively combined with cool air taken from the atmosphere in providing cooling mediums for the cooling systems of an internal combustion engine. The minute intermingling of the air and liquid mediums, which is necessary to the effective conduction of heat from the cylinders of the internal combustion engine, is effected by the novel arrangement of the propeller 66, in that its blades rotate entirely through a mixed body of air and liquid to obtain the desired mixing and circulation of the cooling mediums. It is of course understood that used air escapes by way of the radiator overflow.

Various changes in the shape, size and arrangement of parts may be made to the form of invention herein shown and described, without departing from the spirit of the invention or the scope of the claim.

I claim:

In a cooling system for engines the com-

bination of a housing, a member secured in the housing to subdivide the same into a liquid chamber on one side thereof and a mixing chamber on the other side thereof, said member comprising a pair of spaced walls and tubes extending between the walls providing passageways which communicate the liquid chamber with the mixing chamber, the spaced walls of said member and 10 said housing providing between said walls an air chamber, the wall of said member adjacent the mixing chamber having perfor-

rations therein which communicate the air chamber with the mixing chamber, liquid inlet means for the liquid chamber, air inlet means for the air chamber, and churning means in the mixing chamber adapted upon operation to draw air from the air chamber through the perforations in the wall adjacent said mixing chamber and to 20 draw liquid from the liquid chamber through the passageways of the tubes of said member.

CHARLES A. DU POY.
